LASTING MACHINE

Bernhardt Jorgensen, Marblehead, Mass., assignor to United Shoe Machinery Corporation, Flemington, N. J., a corporation of New Jersey

Application November 24, 1942, Serial No. 466,746

69 Claims. (Cl. 12—14)

This invention relates to lasting machines, and has more particularly in view the provision of a machine for lasting the ball portion of a shoe, i.e., the sides of the forepart extending from the shank or waist portion to the portion customarily lasted in a toe-lasting machine. The invention is accordingly herein illustrated as embodied in a machine intended for that particular use, but it will be understood that in various novel aspects the invention is not limited to machines for lasting that portion of a shoe, but is of more general applicability. It is further contemplated that in the use of the machine herein shown the upper will preferably be fastened in lasted position by cement, but the invention is not dependent upon the use of cement as the fastening means.

In accordance with present practice in shoe manufacture, especially in making shoes in which the margin of the upper is lasted over an insole in parallel relation to the bottom of the last and is fastened to the insole by cement at the toe and ball portions of the shoe, the lasting of the ball portion is frequently performed as a special operation after the shank-lasting operation and usually before the toe-lasting operation. An object of this invention is to provide a machine for that purpose which will operate with uniformly satisfactory results and with a high output while requiring but little skill or care on the part of the operator. To this and other ends, the machine herein shown has wipers which are movable bodily toward each other to lay or wipe the margin of the upper inwardly over the insole at the opposite sides of the ball portion of the shoe, the wipers being supported on bell-crank levers which are movable about axes extending heightwise of the shoe and are operated by means acting thereon with forces directed lengthwise of the shoe. In the illustrative embodiment of the invention the wiper-supporting levers are thus operated by fluid-pressure means acting thereon through other lever mechanism which swings about an axis extending widthwise of the shoe. The shoe is controlled by a holddown engaging the bottom of its forepart and is pressed heightwise against the holddown by a shoe rest which in the construction shown is operated by a treadle acting thereon through a spring. Conveniently, further movement of the treadle, after the shoe rest has been moved into position to clamp the shoe against the holddown, is utilized to admit operating fluid to the fluid-pressure means and thus to start the power operation of the machine. To render the wipers, which in the construction shown are maintained in a heated

condition, effective to apply adequate pressure to the margin of the upper over the insole, provision is afforded for relieving the pressure of the holddown on the shoe to permit the shoe rest to press the shoe more forcibly against the wipers, the holddown being thus controlled by the wiper-operating mechanism. In the construction shown the wipers are resiliently flexible to permit them to bend and thus to conform better to the contour of the bottom of the shoe, especially when the shoe is thus pressed against them by the shoe rest, and mechanism is provided for limiting such bending of portions of the wipers.

In a further aspect, the invention has particularly in view such control of the margin of the upper as to insure that the upper will be lasted in the most satisfactory manner over the last and the insole by the overlaying or wiping means. For this purpose the machine herein shown is provided with members having, in general, the functions of what are commonly known as retarders and which may be so termed, these members being arranged to press the margin of the upper against the edges of the wipers to prevent it from adhering prematurely to the insole and to render the wipers more effective to last the upper tightly over the edge of the insole. Additionally these members serve to insure that the margin of the insole will be properly positioned on the bottom of the last when the upper is lasted inwardly over it. In the construction shown the retarder members are moved outwardly over the insole toward the side edges thereof as the wipers are moved inwardly toward the shoe, mechanism being provided for thus moving the members by the movements of the wiper-carrying levers. After the margin of the upper has been clamped against the incoming wipers by the retarder members, the latter are moved short distances inwardly over the insole by the pressure of the wipers thereon and cooperate with them to apply an inward pull to the upper, whereupon the members are moved heightwise of the shoe out of the paths of the wipers and then outwardly over them, bending the margin of the upper outwardly, as the wipers continue their inward wiping movements.

The above and other features of the invention, including novel shoe-positioning means and various novel details of construction and combinations of parts, will now be more particularly described with reference to the accompanying drawings and thereafter pointed out in the claims.

In the drawings,
Fig. 1 is a view in right-hand side elevation of

a machine in which the invention is embodied, portions of the structure being broken away and the parts being shown in their starting positions;

Fig. 2 is a plan view of the machine with the parts also in their starting positions, the position of a shoe in the machine being indicated diagrammatically by broken lines;

Fig. 3 is a view partly in front elevation and partly in vertical section of the upper portion of the machine with the parts also in their starting positions and the position of the shoe indicated diagrammatically;

Fig. 4 is a view of the upper portion of the machine, partly in right-hand side elevation and partly in section, with the parts in the positions which they occupy when the wipers are at the end of their inward wiping movements;

Fig. 5 is a plan view similar to Fig. 2, but showing the parts as they appear when the wipers are at the end of their inward wiping movements as in Fig. 4; and

Figs. 6, 7, 8 and 9 are views partly in front elevation and partly in section, showing one of the wipers and parts closely associated therewith as they appear at different times in the operation of the machine.

The machine is provided with a column 2 terminating at its upper end in a horizontal shelf 4 on which are secured the lower ends of two vertical frame plates 6 which are spaced apart widthwise of the machine, the greater portion of one of these plates being broken away in Fig. 1. At their upper ends the plates 6 are integral with a horizontal top plate 8, and secured to this top plate is a bifurcated member 10 provided with a pin 12 which serves as a pivotal support for a lever 14 substantially midway between the front and rear ends of the lever. Supported on the front end of the lever 14, which is controlled as hereinafter described, is a holdown 16 arranged to engage the bottom of the forepart of the shoe and to determine the position of the shoe heightwise in the machine. The holdown is provided with a plurality of presser feet 18 (Fig. 3) arranged further to determine by their engagement with the shoe the position of the shoe with respect to tipping movements about axes extending lengthwise and laterally thereof. The holdown 16 has a stem 20 extending upwardly into a socket in the lever 14 and engaged at its upper end by a screw 22 in the lever to determine adjustably the position of the holdown relatively to the lever. A spring 24 in the stem 20 bears at its lower end on a pin 26 which is mounted in the lever and extends through slots 28 in the stem, the spring thus holding the stem at all times against the screw 22. By adjusting the screw, the position of the shoe heightwise relatively to the wipers, herein-after described, may be varied.

The position of the shoe lengthwise is determined by engagement of its toe-end face with an end gage or stop 30, which is secured to the lower face of the top plate 8 by a screw 32 and has therein a slot 34 (Fig. 1) which permits it to be adjusted in directions lengthwise of the shoe as may be required by shoes of different sizes. The machine is further provided with a pair of side gages 36 (Fig. 3) which by contact with the opposite sides of the ball portion of the shoe position the shoe laterally in proper relation to the wipers. These side gages may be made of stiff leather or other suitable material and are preferably curved somewhat both lengthwise and heightwise of the shoe to present convex faces toward the shoe and

thus to facilitate the insertion of the shoe between them. The gages 36 are secured to the upper ends of upwardly extending arms of bell-crank levers 38 which are mounted on pins 40 to swing about axes extending lengthwise of the shoe. The pins 40 are mounted in an arm 42 extending forwardly from a plate 44 which is part of a vertical cylinder 46 mounted in the space between the two frame plates 6 and secured at its lower end to the shelf 4 of the column 2 for a purpose hereinafter described. The two bell-crank levers 38 are provided with arms 48 extending inwardly toward each other and engaged on their upper sides by a flange 50 formed on a screw 52 which is threaded in the supporting arm 42. A spring 54 connected to the two bell-crank levers tends to swing them in directions to separate the side gages 36 from each other and thus holds the arms 48 at all times against the flange 50. By adjustment of the screw 52 the gages 36 are caused to swing equal distances toward or from each other as required for shoes of different widths. By these gages insurance is afforded that the wipers when they are operated will move inwardly substantially equal distances from the opposite side edges of the shoe bottom.

After the shoe has been presented by the operator under the holdown 16 and between the side gages 36 with its toe-end face against the end gage 30, it is clamped against the holdown by a shoe rest 56 which engages the top of the forepart of the shoe. The shoe rest is supported on a lever arm 58 which is fast on a rockshaft 60 mounted in bearings in the side frame plates 6, and fast on one end of this rockshaft is another arm 62. Connected to the arm 62 in the machine herein shown is a treadle 64 by the depression of which the operator moves the shoe rest into engagement with the shoe, the treadle being pivotally mounted on a bracket 66 fast on the base of the column 2. Extending upwardly from the treadle 64 is a rod 68 connected by a turnbuckle 70 to another rod 72 movable lengthwise in a block 74 pivotally mounted on the rear end of the arm 62. Seated on the upper end of the block 74 is a collar 76 against which bears the lower end of a spring 78 engaged at its upper end by a collar 80 adjustably held by a nut 82 on the rod 72. It will thus be seen that in response to depression of the treadle 64 the rods 68 and 72 act through the spring 78 on the arm 62 to swing the shoe rest 56 upwardly into engagement with the shoe. After the shoe has thus been clamped by the shoe rest, the spring 78 is compressible to permit further depression of the treadle for a purpose hereinafter described, and when it is thus compressed it serves to hold the shoe rest forcibly against the shoe during the power operation of the machine. The shoe rest 56 is mounted on a pin 84 which permits it to tip laterally and thus to adjust itself to the shoe against the resistance of a leaf spring 86 which is fast on the arm 58 and bears upwardly against it to maintain it normally in a central position with respect to such tipping movement.

For wiping the margin of the upper inwardly over the insole along the opposite sides of the ball portion of the shoe the machine is provided with a pair of wipers 88 consisting, in the construction herein shown, of comparatively thin steel plates resiliently flexible in directions heightwise of the shoe. These plates are secured, each by a pair of bolts 90 (Fig. 2), to forwardly extending arms 92 of bell-crank levers

94 pivotally mounted on studs 96 supported on the top frame plate 8 to swing about axes extending heightwise of the shoe. The bell-crank levers 94 have other arms 98 extending generally widthwise of the shoe in crossed relation to each other and connected respectively by links 100 to upwardly extending arms 102 of other bell-crank levers 104 mounted on a rod 106 to swing about an axis extending widthwise of the shoe, this rod being supported on an arm 108 extending rearwardly from the previously mentioned plate 44. The bell-crank levers 104 have other forwardly extending arms 110 connected by links 112 to a rod 114 which extends through vertical slots 116 in the sides of the previously mentioned cylinder 46 and also through a piston 118 in the cylinder. In response to upward movement of this piston, therefore, wiper-operating movements are imparted through the bell-crank levers 104 to the bell-crank levers 94, the wiper-carrying arms 92 of the latter being swung inwardly toward each other.

Such upward movement of the piston 118 is effected by operating fluid admitted to the lower end of the cylinder 46, the construction herein shown being intended for the use of compressed air as the operating fluid, although liquid may be used if desired. The lower end of the cylinder 46 is connected by a conduit 120 to 25 valve mechanism 122 which controls the admission and exhaust of air to and from the cylinder. The valve mechanism comprises a tube 124 clamped between two blocks 126 and 128 fast on an inclined arm 130 extending rearwardly from the shelf 4. One end of the tube 124 is in communication through a passageway in the block 126 with the conduit 120, and the other end of the tube is in communication with a conduit 132 leading from a source of compressed 40 air supply. This may be conveniently a general source of supply with which a shoe factory is equipped, or if desired a special motor-driven pump may be provided for supplying the compressed air. Midway of its length the tube 124 has a partition 134 extending across it, and extending through the wall of the tube at the opposite sides of this partition respectively are ports 136 and 138. Movable lengthwise along the tube is a sleeve valve 140 provided with an 45 annular chamber 142 arranged, when the valve is in one position, to provide communication between the ports 136 and 138 and thus to admit compressed air to the cylinder 46. When the valve is in the position shown in Fig. 1 the ports 136 are open to the atmosphere and the piston 118 is at the lower end of the cylinder, in which position it is maintained by springs 144 connected to the arms 110. In the construction herein shown, movement of the valve into 50 position to admit compressed air to the cylinder is effected by further movement of the treadle 64 after the shoe rest 56 has been moved by the treadle into shoe-clamping position as hereinbefore described. For this purpose an arm 146 is pivotally mounted at 148 on the arm 130 which supports the valve mechanism and is provided with a pin 150 extending into a groove 152 in the sleeve valve 140 to move the valve along the tube 124 by swinging movement of the arm. The 55 valve is maintained normally in its initial position, determined by its engagement with the block 128, by means of a spring 154 connected to a pin 156 carried by the arm 146. This pin extends through a slot 158 in an inclined link 75

160 which is pivotally connected at its lower end to a collar 161 fast on the previously mentioned treadle-operated rod 68. When this rod is moved downwardly, therefore, downward movement is imparted to the link 160, but by reason of the slot 158 in the link no movement is imparted to the valve-operating arm 146 until after the shoe rest 56 has been moved into clamping position. Further movement of the treadle 64 thereafter, by which movement the spring 78 is compressed as hereinbefore described, serves through the link 160 to operate the arm 146 and thereby to move the valve 140 into position to admit compressed air to the cylinder 46 and thus to cause the wipers to be operated. When the treadle is released by the operator after the operation of the machine on a shoe, it is raised by a spring 162 connected to a collar 163 fast on the rod 68, and by the action of this spring 20 return movement is imparted to the link 160. This permits the valve 140 to be moved by the spring 154 into position to open the ports 136 to the atmosphere and thus to permit exhaust of the air from the cylinder 46, the wipers being returned to their initial positions by the action of the springs 144. Return movement of the treadle is limited by engagement of a screw 164 threaded in an arm 165 fast on one end of the shaft 60 with a lug 166 on one of the frame plates 6.

When a shoe is pressed upwardly against the holdown 16 by the shoe rest 56, the lever 14 is held rigidly against movement in response to the pressure of the shoe on the holdown by an arm 168 mounted to swing about the rod 106 and provided with a roll 170 which engages the lower face of the rear end of the lever. A spring 172 connected to the arm holds it normally in an upright position determined by engagement of the roll 170 with a lug 174 on the lever. When the wipers 88 are over the shoe bottom it is desirable to increase their pressure on the shoe in order to insure that all portions of the margin of the upper which are wiped inwardly over the insole by them will be pressed satisfactorily down on the insole. This is particularly important for the reason that the holdown 16 is preferably so adjusted as to provide substantial clearance between the wipers and the insole to assist in guarding against displacement of the margin of the insole by the inward movements of the wipers. To provide for such increase of pressure of the wipers on the shoe, the pressure of the holdown on the shoe is relieved when the wipers have substantially or nearly completed their inward wiping movements, thus permitting the shoe rest 56 to press the shoe more forcibly up against the wipers under the influence of the spring 78. For this purpose the arm 168 is swung rearwardly far enough to release the lever 14. To effect such swinging movement of the arm 168 the upwardly extending arms 102 of the wiper-operating bell-crank levers 104 carry a yoke member 176 (Fig. 2) which is secured to pins 178 whereby the links 100 are connected to the arms 102. The yoke member 176 carries a screw 180 arranged to engage the arm 168, this screw by its adjustment determining the time with respect to the operative movements of the wipers when the lever 14 is released. This lever is controlled by a spring 182 which tends to swing its front end downwardly and holds it normally in a position determined by its engagement with a stop 184 on the top plate 8.

This spring is a comparatively light spring and does not prevent such upward movement of the shoe by the stronger spring 78 as to cause the wipers to apply the desired increased pressure to the margin of the upper when the lever 14 is released by the arm 168.

By reference to Fig. 2 it will be seen that the bolts 90 which secure the flexible wipers 88 to the arms 92 are located substantial distances widthwise of the shoe from the shoe-engaging portions of the wipers, and these portions of the wipers are accordingly left free throughout their lengths to be flexed or bent by the increased upward pressure of the shoe against them when the lever 14 is released as above described. This permits the wipers to conform satisfactorily to the more or less convex lengthwise and lateral curvatures of the bottom of the ball portion of a shoe and thus to apply adequate pressure to all portions of the margin of the upper on which they act. Preferably, however, as shown, the machine is provided with means for preventing any excessive upward bending of the shoe-engaging portions of the wipers as a whole, especially in such manner as to incline them too much laterally of the shoe, this means comprising screws 186 and 188 mounted in inwardly extending lugs on the arms 92 and arranged to engage the top faces of the wipers at their front and rear ends respectively. By reference to Figs. 1 and 3 it will be noted that the lower ends of the screws are normally positioned some distances above the wipers. The support which the screws thus afford for the front and rear ends of the wipers after they engage them contributes to such further bending of the portions of the wipers between the screws as to conform properly to the lengthwise curvature of the bottom of the ball portion of the shoe.

To assist in preventing the wiper-carrying arms 92 from being sprung upwardly by the upward pressure of the shoe on the wipers, there are fast on the top of the frame plate 8 blocks 190 underneath portions of which the arms are moved in operating the wipers, as illustrated in Fig. 5. These blocks are provided with shoulders 192 (Fig. 2) which by engagement with the arms 92 limit the operative movements of the wipers. In the construction shown the wipers are maintained in a heated condition, as is preferable in lasting with cement, by electrical heating units 194 mounted in blocks 196 which are secured to the lower faces of the wipers in locations far enough outwardly to avoid contact with the side gages 36 when the wipers are at the limits of their inward wiping movements. The heating units are supplied with current from a suitable source through flexible conduits 198 attached to the blocks 196. The studs 96 about which the wipers are swung are such a distance apart that the portions of the wipers which act on the margin of the upper have components of movement lengthwise of the shoe toward its toe end, which is desirable in view of the inward curvature of the edge of the shoe bottom heelwardly of the ball line. Since shoes presented to the machine may sometimes have therein upwardly standing pulling-over tacks in the vicinity of the ends of the tip seam, the wipers have therein recesses 200 to prevent them from disturbing these tacks.

Arranged to cooperate with the wipers 88 to control the margin of the upper as it is wiped inwardly over the insole by the wipers are re-

tarder members 202 which press or clamp the margin of the upper in upstanding position against the edges of the wipers prior to and at the beginning of the wiping operation and serve 5 additionally to press the margin of the insole along the ball portion of the shoe down on the bottom of the last. These members are extended substantial distances lengthwise of the shoe and are curved laterally of the shoe similarly to 10 corresponding portions of the wiping edges of the wipers. They are supported by carrier arms 204 which are mounted on studs 206 on the top frame plate 8 to swing toward and from each other in directions widthwise of the shoe. Each 15 arm 204 is made up of a plurality of parts comprising a hollow bar 208 in one end of which is secured a stem extending forwardly from a member 210 mounted on the stud 206 and in the other end of which is secured a stem extending rearwardly from a member 212 which supports the retarder member 202. The member 212 is movable relatively to the bar 208 to adjust the retarder member in directions lengthwise of the shoe, and it is held in adjusted relation to the bar by a clamp screw 214 threaded in its 20 stem and extending through a slot 216 in the bar. A spring 218 connected to the two arms 204 tends to swing them inwardly toward each other and holds them initially in positions determined by engagement of the retarder members 202 with the sides of the holddown 16. From 25 these positions the arms are swung outwardly to carry the retarder members toward the opposite side edges of the insole by means hereinafter described. Each of the retarder members has an offset upwardly extending cylindrical portion 220 mounted in a socket in the supporting member 212 and engaged by a spring 222 which tends to move the member downwardly, the limit 30 of such downward movement being determined by a collar 224 fast on the upper end of a stem 226 extending upwardly from the cylindrical portion of the retarder member, the collar normally engaging the top face of the member 212. 35 Initially the retarder members 202 extend downwardly short distances beyond the holddown 16, as illustrated in Fig. 3, and they are moved upwardly against the resistance of the springs 222 by pressure of the shoe thereon when it is 40 pressed upwardly by the shoe rest 56. Insurance is thus afforded that the retarder members will press downwardly on the insole when they are moved outwardly toward the side edges of the insole. Connected to pins on the collars 224 and 45 on the arms 204 are springs 228 (Fig. 2) which initially hold the retarder members in definite positions with respect to turning movements about the axes of the stems 226 but permit the members to turn and adjust themselves to the 50 wipers when the margin of the upper is pressed against them by the wipers.

For swinging the arms 204 outwardly to carry the retarder members toward the side edges of the insole there are provided other arms 230 mounted on studs 232 on the frame plate 8 for swinging movements in directions widthwise of the shoe, these arms being connected to the arms 204 by links 234 constructed as hereinafter 55 described. Also mounted to swing about the studs 232, above the arms 230, are plates 236. Each of these plates is held at all times in predetermined adjusted relation to the arm 230 associated therewith by a spring 238 mounted in a socket in the arm and engaging a lug 240 on the plate and by a pin 242 extending upwardly 60

from the arm through a slot 244 in the plate and engaged by a screw 246 threaded in the plate. Each plate is provided with a projection or nose 248 arranged to be engaged by a finger 250 formed on or secured to the adjacent wiper-carrying arm 92. When the two arms 92, therefore, are swung inwardly to operate the wipers the fingers 250 have a cam-like action on the plates 236 to swing these plates and the arms 230 connected therewith in outward directions, thus swinging the arms 204 outwardly against the resistance of the spring 218. In this manner the retarder members 202 are moved outwardly over the insole toward the wipers as the wipers are being moved inwardly toward the side edges of the insole. In their outward movements the retarder members serve to spread from over the insole any portion of the margin of the upper which may extend inwardly over it. At the time when the outwardly moving retarder members and the inwardly moving wipers arrive in positions to clamp the upstanding margin of the upper between them the retarder members preferably are so located that their upper-engaging faces are positioned slightly farther outward than the side edges of the insole, so as to detach from the edges of the insole any portion of the upper which may have adhered prematurely thereto. In order that the retarder members may thus be properly positioned relatively to the side edges of the insole in operating on shoes of different widths, the plates 236 are adjustable about the studs 232 relatively to the arms 230 by means of the screws 246. That is, by such adjustment of the plates their projections 248 may be variably spaced initially from the faces 252 of the fingers 250 which act thereon, thus varying the time in the inward movements of the wiper-carrying arms 92 when the arms begin to impart outward movements to the retarder members and therefore varying the distances these members have been moved at the time when the margin of the upper is first clamped against them by the wipers.

Each of the links 234 comprises a coupling member 254 mounted on a stud 256 on the end of the arm 230 associated therewith for swinging movements in directions heightwise of the shoe, and a bar 258 pivotally mounted at one end on a pin 260 carried by the coupling member 254 and extending at right angles to the stud 256. Near its other end the bar 258 is so shaped as to extend downwardly and then inwardly under the cylindrical portion 220 of the retarder member 202, its inwardly extending portion being provided with a slot 262 through which a headed stud 264 extends downwardly from the cylindrical portion 220. A spring 266 connected at one end to a screw 268 threaded in the bar 258 and at its other end to the member 212 of the arm 204 tends to swing the arm outwardly and holds it normally in a relation to the bar 258 determined by engagement of the stud 264 with the bar at the outer end of the slot 262. As the wipers continue their inward movements after having clamped the upstanding margin of the upper against the retarder members 202 they force these members inwardly against the resistance of the springs 266 by the pressure applied thereto through the margin of the upper, the studs 264 being carried inwardly along the slots 262. In this manner the wipers and the retarder members cooperate to apply an inward pull to the margin of the upper, thus drawing the upper

tightly over the edge of the insole. Shortly after the wipers begin to wipe the margin of the upper inwardly over the insole, however, the retarder members are lifted against the resistance of the springs 222 to withdraw them from the paths of the wipers. For this purpose there are mounted on the bars 258 of the links 234 members 270 having portions extending downwardly through slots 272 in the bars and carrying rolls 274 which are engaged by the wiper-carrying arms 92 to swing the links 234 upwardly about the studs 256 and thereby to lift the retarder members 202. The members 270 are clamped on the bars 258 by the previously mentioned screws 268, these screws extending through slots 276 in the members to permit the latter to be adjusted to determine precisely the time in the inward movements of the arms 92 when the arms act on the rolls to lift the retarder members. When the retarder members have thus been lifted they are moved outwardly over the wipers by contraction of the springs 266 and also by continued action of the fingers 250 on the plates 236 and the arms 230 as the wipers continue their inward movements under them, the members acting early in such outward movements to bend the margin of the upper outwardly over the edges of the wipers and thus to increase the effectiveness of the wipers in wiping the upper tightly and smoothly over the insole. It will be evident that when the wiper-carrying arms 92 act on the rolls 274 the links 234 serve as levers through which the retarder members are lifted against the resistance of the springs 222.

The manner of operation of the machine will now be briefly summarized. The operator presents a shoe to the machine between the side gages 36 with its toe-end face against the end gage 30, the side gages having been adjusted by the screw 52 into proper positions for determining by engagement with the sides of the ball portion of the shoe the position of the forepart of the shoe laterally. The shoe is thus presented, moreover, with the insole in contact with the two retarder members 202 which extend downwardly beyond the holdown 16. By depression of the treadle 64 the operator then moves the shoe rest 56 upwardly into engagement with the top of the forepart of the shoe, and by the pressure of the shoe rest on the shoe the latter is forced upwardly into engagement with the holdown 16, lifting the retarder members 202 against the resistance of the springs 222. Further depression of the treadle then serves to compress the spring 78 and to move the valve 140 into position to admit compressed air to the cylinder 46 to impart upward movement to the piston 118. By the action of the piston the bell-crank levers 94 are operated to swing their wiper-carrying arms 92 inwardly toward each other. As the arms 92 are swung inwardly their fingers 250 have a cam-like action on the plates 236 to impart outward swinging movements to the arms 230, and these arms act through the links 234 to impart outward swinging movements also to the arms 204 which carry the retarder members 202. The retarder members are thus moved outwardly over the insole toward its side edges while pressing downwardly on the insole as the wipers 88 are being moved inwardly toward them. As the retarder members are thus moved outwardly they serve to spread from over the insole any portion of the margin of the upper which may extend inwardly over it, and when they arrive in positions where their upper-engaging faces are positioned

slightly farther outward than the side edges of the insole, as illustrated in Fig. 6, the wipers 83 arrive in positions to clamp the upstanding margin of the upper against them. As the wipers continue their inward movements they force the members 202 inwardly against the resistance of the springs 266 by their pressure on the members, as permitted by the slots 262 in the bars 258, and in this operation the wipers and the retarder members serve to apply an inward pull to the margin of the upper over the extreme edge of the insole as illustrated in Fig. 7. Slightly before the parts arrive in the positions illustrated in Fig. 7 the wiper-carrying arms 92 begin to act on the rolls 274 to swing the links 234 upwardly and thus to lift the retarder members 202 to withdraw them from the paths of the wipers. When these members are clear of the wipers they are moved outwardly over them by the continued action of the fingers 250 on the plates 236 and by contraction of the springs 266, and early in such outward movements the retarder members serve to bend the margin of the upper outwardly over the edges of the wipers, as illustrated in Fig. 8, thus increasing the effectiveness of the wipers in wiping the margin of the upper tightly inward over the insole. Near the end of the inward movements of the wipers the arm 168 is swung far enough rearwardly by the action of the screw 180 thereon to release the holdown-supporting lever 14, as illustrated in Fig. 4, whereupon the spring 78 acts through the shoe rest 56 to force the shoe farther upwardly, thus increasing the pressure of the wipers on the margin of the upper and causing them to bend into better conformity to the contour of the bottom of the shoe. The bending of the opposite ends of the wipers is limited by the screws 186 and 198, as illustrated in Fig. 9, after which further bending of the portions of the wipers between the screws may take place to conform better to the lengthwise curvature of the bottom of the shoe. The operator preferably holds the treadle depressed long enough to cause the heated wipers to continue for a few seconds their pressure on the overwiped margin of the upper, thus allowing more time for the cement to set while the upper is pressed smoothly on the insole. When the operator releases the treadle the shoe rest 56 is swung downwardly away from the shoe by the action of the spring 162 on the treadle rod 68 and the valve 140 is returned by the spring 154 into position to release the compressed air from the cylinder 46. The wipers are then returned to their starting positions by the springs 144 and the retarder members 202 are returned to their initial positions against the sides of the holdown 16 by the spring 218, the operator having lowered the shoe to clear these members.

Having described the invention, what I claim as new and desire to secure by Letters Patent of the United States is:

1. In a lasting machine, wipers movable bodily toward each other to wipe the margin of an upper inwardly over an insole at the opposite sides of the ball portion of a shoe, levers mounted to swing about axes extending heightwise of the shoe, said levers having arms arranged to extend generally lengthwise of the shoe for thus moving said wipers and having other arms arranged to extend generally widthwise of the shoe, and means for operating the levers by forces applied to said other arms in directions generally lengthwise of the shoe.

2. In a lasting machine, wipers movable bodily

toward each other to wipe the margin of an upper inwardly over an insole at the opposite sides of the ball portion of a shoe, levers mounted to swing about axes extending heightwise of the shoe, said 5 levers having arms arranged to extend generally lengthwise of the shoe for thus moving said wipers and having other arms arranged to extend generally widthwise of the shoe, and means connected to said other arms and mounted to 10 swing about an axis extending widthwise of the shoe to operate said levers.

3. In a lasting machine, wipers movable bodily toward each other to wipe the margin of an upper inwardly over an insole at the opposite sides of the ball portion of a shoe, levers mounted to 15 swing about axes extending heightwise of the shoe, said levers having arms arranged to extend generally lengthwise of the shoe and supporting said wipers and having other arms arranged to 20 extend generally widthwise of the shoe in crossed relation to each other, and means movable lengthwise of the shoe and connected to said crossed arms for operating said levers.

4. In a lasting machine, members movable bodily toward each other to lay the margin of an upper inwardly over an insole at the opposite sides of the ball portion of a shoe, levers mounted to 25 swing about axes extending heightwise of the shoe for thus moving said members, and cylinder-and-piston mechanism for operating said levers by fluid pressure.

5. In a lasting machine, members movable bodily toward each other to lay the margin of an upper inwardly over an insole at the opposite sides of the ball portion of a shoe, levers mounted to 35 swing about axes extending heightwise of the shoe, said levers having arms arranged to extend generally lengthwise of the shoe and supporting said members and having other arms arranged to 40 extend generally widthwise of the shoe, and cylinder-and-piston mechanism for operating said levers by fluid pressure through forces applied to said other arms in directions generally lengthwise of the shoe.

6. In a lasting machine, members movable bodily toward each other to lay the margin of an upper inwardly over an insole at the opposite sides of the ball portion of a shoe, levers mounted to swing about axes extending heightwise of the shoe, said levers having arms arranged to 50 extend generally lengthwise of the shoe and supporting said members and having other arms arranged to extend generally widthwise of the shoe, mechanism connected to said other arms and mounted to swing about an axis extending widthwise of the shoe to operate said levers, and cylinder-and-piston means for operating said mechanism by fluid pressure.

7. In a lasting machine, the combination with 60 means for laying the margin of an upper inwardly over an insole at the opposite sides of the forepart of a shoe, of an end gage for determining the position of the shoe lengthwise relatively to said overlaying means by contact with the toe-end face of the upper, and side gages for positioning the shoe laterally by contact with the upper at the opposite sides of the forepart, all said gages being arranged to maintain contact with the upper throughout the operation of said overlaying means on the shoe.

8. In a lasting machine, the combination with 65 means for laying the margin of an upper inwardly over an insole at the opposite sides of the forepart of a shoe, of an end gage and side gages arranged to position the shoe relatively to said

overlaying means by contact with the toe-end face and the opposite sides of the forepart of the upper respectively and to maintain such contact throughout the operation of the overlaying means on the shoe, said end gage being adjustable in directions lengthwise of the shoe relatively to the side gages and the side gages being adjustable toward or from each other.

9. In a lasting machine, the combination with means for laying the margin of an upper inwardly over an insole at the opposite sides of the forepart of a shoe, of side gages arranged to position the shoe relatively to said overlaying means by contact with the upper at the opposite sides of the forepart and to maintain such contact throughout the operation of the overlaying means on the shoe, and means comprising a member common to said side gages for adjusting them equal distances toward or from each other.

10. In a lasting machine, the combination with means for laying the margin of an upper inwardly over an insole at the opposite sides of the forepart of a shoe, of side gages arranged to position the shoe relatively to said overlaying means by contact with the upper at the opposite sides of the forepart and to maintain such contact throughout the operation of the overlaying means on the shoe, levers mounted to swing about axes extending lengthwise of the shoe and having arms extending heightwise of the shoe and supporting said gages, and means comprising a member common to said levers for swinging them to adjust the gages equal distances toward or from each other.

11. In a lasting machine, wipers for wiping the margin of an upper inwardly over an insole on a last, means for increasing the pressure of said wipers on the margin of the upper heightwise of the shoe when they are over the shoe bottom, the wipers being resiliently flexible to permit them to bend in conformity to the contour of the bottom of the shoe when the pressure is thus increased, and means for adjustably limiting such bending of portions of the wipers.

12. In a lasting machine, wipers for wiping the margin of an upper inwardly over an insole on a last, means for increasing the pressure of said wipers on the margin of the upper heightwise of the shoe when they are over the shoe bottom, the wipers being resiliently flexible to permit them to bend in conformity to the contour of the bottom of the shoe when the pressure is thus increased, and limit stops into contact with which portions of the wipers are moved by such bending thereof.

13. In a lasting machine, wipers for wiping the margin of an upper inwardly over an insole at the opposite sides of the ball portion of a shoe, means for increasing the pressure of said wipers on the margin of the upper heightwise of the shoe when they are over the shoe bottom, the wipers being resiliently flexible to permit them to bend throughout the lengths of their upper-engaging portions in conformity to the contour of the bottom of the shoe when the pressure is thus increased, and means for limiting the bending of the opposite ends of the wipers measured lengthwise of the shoe while permitting further bending thereof in locations between said opposite ends.

14. In a lasting machine, wipers for wiping the margin of an upper inwardly over an insole at the opposite sides of the ball portion of a shoe, means for increasing the pressure of said wipers on the margin of the upper heightwise of the

shoe when they are over the shoe bottom, the wipers being resiliently flexible to permit them to bend throughout the lengths of their upper-engaging portions in conformity to the contour of the bottom of the shoe when the pressure is thus increased, and adjustable stops into contact with which the opposite ends of the wipers measured lengthwise of the shoe are moved by such bending thereof to limit the bending of those

5 portions while permitting further bending in locations between said opposite ends.

10 15. In a lasting machine, means movable to lay the margin of an upper inwardly over an insole on a last, a holddown for engaging the insole, a shoe rest for pressing the shoe heightwise against said holddown, lever mechanism movable to operate said overlaying means, and means controlled by said lever mechanism for relieving the pressure of the holddown on the insole to permit the shoe to be pressed more forcibly against the overlaying means by said shoe rest.

15 20 25 30 35. In a lasting machine, members movable to lay the margin of an upper inwardly over an insole on a last at the opposite sides of the last, a holddown for engaging the insole, a shoe rest for pressing the shoe heightwise against said holddown, levers mounted to swing about axes extending heightwise of the shoe to operate said overlaying members, mechanism movable lengthwise of the shoe to operate said levers, and means controlled by said mechanism for relieving the pressure of the holddown on the insole to permit the shoe to be pressed more forcibly against said members by the shoe rest.

40 45 50 55 60 65 70. 17. In a lasting machine, means movable to lay the margin of an upper inwardly over an insole on a last, a holddown for engaging the insole, a shoe rest for pressing the shoe heightwise against said holddown, a lever supporting said holddown and mounted to swing in directions heightwise of the shoe, mechanism movable to operate said overlaying means, and means for controlling said lever by said mechanism to relieve the pressure of the holddown on the insole and thus to permit the shoe to be pressed more forcibly against the overlaying means by said shoe rest.

18. In a lasting machine, means movable to lay the margin of an upper inwardly over an insole on a last, a holddown for engaging the insole, a shoe rest for pressing the shoe heightwise against said holddown, a lever controlling said holddown and mounted to swing in directions heightwise of the shoe, a member arranged to serve as an abutment for said lever to support the holddown against the pressure of said shoe rest, and means for moving said member to relieve the pressure of the holddown on the insole as an incident to the operation of said overlaying means and thereby to permit the shoe to be pressed more forcibly against the overlaying means by said shoe rest.

19. In a lasting machine, means movable to lay the margin of an upper inwardly over an insole on a last, a holddown for engaging the insole, a shoe rest for pressing the shoe heightwise against said holddown, a lever supporting said holddown and mounted to swing in directions heightwise of the shoe, and means for controlling said lever movable in predetermined time relation to said overlaying means to relieve the pressure of the holddown on the insole and thereby to permit the shoe to be pressed more forcibly against the overlaying means by said shoe rest.

70 75 80 85 90 95 100. 20. In a lasting machine, wipers movable to

wipe the margin of an upper inwardly over an insole at the opposite sides of the ball portion of a shoe, a holddown for engaging the bottom of the forepart of the shoe, a shoe rest for engaging the top of the forepart of the shoe and for pressing the shoe heightwise against said holddown, a lever supporting said holddown and mounted to swing in directions heightwise of the shoe, a member arranged to serve as an abutment for said lever to control the holddown, and means for moving said member in predetermined time relation to the wipers to relieve the pressure of the holddown on the shoe and thereby to permit the shoe to be pressed more forcibly against the wipers by said shoe rest.

21. In a lasting machine, power-operated means movable to lay the margin of the forepart of an upper inwardly over an insole on a last, a holddown for engaging the insole, a shoe rest for engaging the top of the forepart of the shoe and for pressing the shoe heightwise against said holddown, means enabling the operator thus to operate said shoe rest and thereafter to maintain its pressure on the shoe during the power operation of the machine, and automatic means for relieving the pressure of the holddown on the insole to permit the shoe to be pressed more forcibly against the overlaying means by said shoe rest.

22. In a lasting machine, power-operated wipers movable to wipe the margin of an upper inwardly over an insole on a last at the opposite sides of the last, a holddown for engaging the insole, a shoe rest movable in a direction heightwise of the shoe to press the shoe against said holddown, a member movable by the operator thus to move said shoe rest, a spring arranged to transmit the force of said member to the shoe rest and to be subjected to stress by the movement of said member, and automatic means for relieving the pressure of the holddown on the insole to permit the shoe to be pressed more forcibly against the wipers by the action of said spring on the shoe rest.

23. In a lasting machine, power-operated means movable to lay the margin of an upper inwardly over an insole on a last, a holddown for engaging the insole, a shoe rest movable into position to clamp the shoe against said holddown, a member movable by the operator thus to move said shoe rest into clamping position, and means for starting the power operation of the machine in response to further movement of said member after such movement of the shoe rest.

24. In a lasting machine, means movable to lay the margin of an upper inwardly over an insole on a last, cylinder-and-piston mechanism for thus operating said overlaying means by fluid pressure, means movable into position to clamp and hold the shoe for the operation of said overlaying means thereon, a member movable by the operator thus to move said clamping means, and a valve movable to admit operating fluid to said cylinder-and-piston mechanism in response to further movement of said member after the clamping of the shoe.

25. In a lasting machine, means movable to lay the margin of an upper inwardly over an insole on a last, cylinder-and-piston mechanism for thus operating said overlaying means by fluid pressure, a holddown for engaging the insole, a shoe rest movable into position to clamp the shoe against said holddown, a member movable by the operator thus to move said shoe rest, and a valve movable to admit operating fluid to said

cylinder-and-piston mechanism in response to further movement of said member after the clamping of the shoe by the shoe rest.

26. In a lasting machine, wipers movable to wipe the margin of an upper inwardly over an insole at the opposite sides of the ball portion of a shoe, power-operated means for thus operating the wipers, a holddown for engaging the bottom of the forepart of the shoe, a shoe rest for engaging the top of the forepart of the shoe and for clamping the shoe against said holddown, a member movable by the operator to move said shoe rest into position thus to clamp the shoe against the holddown, and means for starting the power operation of the machine in response to further movement of said member after such movement of the shoe rest.

27. In a lasting machine, power-operated means movable to lay the margin of an upper inwardly over an insole on a last, a holddown for engaging the insole, a shoe rest movable into position to press the shoe heightwise against said holddown, a member movable by the operator thus to move said shoe rest, a spring yieldable to permit further movement of said member and arranged to hold the shoe rest pressed against the shoe, means for starting the power operation of the machine in response to the further movement of said member, and automatic means for relieving the pressure of the holddown on the shoe to permit the shoe to be pressed more forcibly against the overlaying means by the action of said spring on the shoe rest.

28. In a lasting machine, wipers movable to wipe the margin of an upper inwardly over an insole at the opposite sides of the ball portion of a shoe, power-operated means for thus operating said wipers, a holddown for engaging the bottom of the forepart of the shoe, a shoe rest for engaging the top of the forepart of the shoe and for clamping the shoe against said holddown, a member movable by the operator to move said shoe rest into position thus to clamp the shoe against the holddown, a spring yieldable to permit further movement of said member and arranged to hold the shoe rest pressed against the shoe, means for starting the power operation of the machine in response to the further movement of said member, and automatic means for relieving the pressure of the holddown on the shoe to permit the shoe to be pressed more forcibly against the wipers by the action of said spring on the shoe rest.

29. In a lasting machine, wipers movable to wipe the margin of an upper inwardly over an insole at the opposite sides of the ball portion of a shoe, cylinder-and-piston mechanism for thus operating said wipers by fluid pressure, a holddown for engaging the bottom of the forepart of the shoe, a shoe rest for engaging the top of the forepart of the shoe and for clamping the shoe against said holddown, a member movable by the operator to move said shoe rest into position thus to clamp the shoe against the holddown, a spring yieldable to permit further movement of said member and arranged to hold the shoe rest pressed against the shoe, means for admitting operating fluid to said cylinder-and-piston mechanism in response to the further movement of said member, and automatic means for relieving the pressure of the holddown on the shoe to permit the shoe to be pressed more forcibly against the wipers by the action of said spring on the shoe rest.

30. In a lasting machine, means movable to

lay the margin of an upper inwardly over an insole on a last, a member arranged to engage the insole to press its margin on the bottom of the last and also to press the margin of the upper against said overlaying means to control the upper, said member being movable inwardly over the insole in response to pressure of the overlaying means thereon, a support for said member movable with it when it is thus moved inwardly over the insole, and means to cause said member to move heightwise of the shoe relatively to said support out of the path of the overlaying means in the course of the inward movement of said overlaying means.

31. In a lasting machine, means movable to lay the margin of an upper inwardly over an insole on a last, a member arranged to engage the insole to press its margin on the bottom of the last and also to press the margin of the upper against said overlaying means to control the upper, said member being movable inwardly over the insole in response to pressure of the overlaying means thereon, a support for said member movable with it when it is thus moved inwardly over the insole, means for moving said member heightwise of the shoe relatively to said support out of the path of the overlaying means in the course of the inward movement of said overlaying means, and means for moving said member outwardly over the overlaying means upon its withdrawal from said path.

32. In a lasting machine, wipers movable to wipe the margin of an upper inwardly over an insole on a last at the opposite sides of the last, retarder members for pressing the margin of the upper against the wipers to control the upper, said retarder members being movable inwardly over the insole by pressure of the wipers thereon, carriers for said members movable with them when they are thus moved inwardly by the wipers, and means to cause said members to move heightwise of the shoe relatively to said carriers out of the paths of the wipers in the course of the inward movements of the wipers.

33. In a lasting machine, wipers movable to wipe the margin of an upper inwardly over an insole on a last at the opposite sides of the last, retarder members for pressing the margin of the upper against the wipers to control the upper, said retarder members being movable inwardly over the insole by pressure of the wipers thereon, carriers for said members movable with them when they are thus moved inwardly by the wipers, means to cause said members to move heightwise of the shoe relatively to said carriers out of the paths of the wipers in the course of the inward movements of the wipers, and means for operating said carriers to carry the members outwardly over the wipers when they are thus clear of the wipers.

34. In a lasting machine, wipers movable to wipe the margin of an upper inwardly over an insole on a last at the opposite sides of the last, retarder members for pressing the margin of the upper against the wipers to control the upper, said retarder members being movable inwardly over the insole by pressure of the wipers thereon, carriers for said members movable with them when they are thus moved inwardly by the wipers, means arranged to act independently of the pressure of the wipers on said members to move them heightwise of the shoe relatively to said carriers out of the paths of the wipers in the course of the inward movements of the wipers, and means for operating said carriers to

carry the members outwardly over the wipers when they are thus clear of the wipers.

35. In a lasting machine, wipers movable to wipe the margin of an upper inwardly over an insole on a last at the opposite sides of the last, retarder members for pressing the margin of the upper against the wipers to control the upper, said retarder members being movable inwardly over the insole by pressure of the wipers thereon, arms carrying said members and mounted for swinging movements widthwise of the shoe about axes extending heightwise of the shoe, said arms being thus movable with said members when the members are moved inwardly over the insole by the wipers, and means to cause said members to move heightwise of the shoe away from the insole relatively to said arms in the course of the inward movements of the wipers.

36. In a lasting machine, wipers movable to wipe the margin of an upper inwardly over an insole on a last at the opposite sides of the last, retarder members for pressing the margin of the upper against the wipers to control the upper, said retarder members being movable inwardly over the insole by pressure of the wipers thereon, arms carrying said members and mounted for swinging movements widthwise of the shoe about axes extending heightwise of the shoe, said arms being thus movable with said members when the members are moved inwardly over the insole by the wipers, means for moving said members heightwise of the shoe out of the paths of the wipers in the course of the inward movements of the wipers, and means for swinging said arms to carry the members outwardly over the wipers when they are thus clear of the wipers.

37. In a lasting machine, wipers movable to wipe the margin of an upper inwardly over an insole on a last at the opposite sides of the last, retarder members for pressing the margin of the upper against the wipers to control the upper, arms mounted for swinging movements widthwise of the shoe about axes extending heightwise of the shoe to carry said retarder members outwardly toward the edge of the insole, means for thus moving said arms, and spring means against the resistance of which the retarder members are movable heightwise of the shoe away from the insole relatively to said arms in the course of the inward movements of the wipers.

38. In a lasting machine, wipers movable to wipe the margin of an upper inwardly over an insole on a last at the opposite sides of the last, retarder members for pressing the margin of the upper against the wipers to control the upper, arms mounted for swinging movements widthwise of the shoe about axes extending heightwise of the shoe to carry said retarder members outwardly toward the edge of the insole, means for thus moving said arms, the arms being reversely movable with said retarder members in response to pressure of the wipers on said members, and means for moving said members heightwise of the shoe away from the insole relatively to said arms in predetermined time relation to the wiping movements of the wipers.

39. In a lasting machine, wipers movable to wipe the margin of an upper inwardly over an insole on a last at the opposite sides of the last, retarder members for pressing the margin of the upper against the wipers to control the upper, arms mounted for swinging movements widthwise of the shoe about axes extending heightwise of the shoe to carry said retarder members outwardly toward the edge of the insole, means

for thus moving said arms, the arms being reversely movable with said retarder members in response to pressure of the wipers on said members, and means for moving said members heightwise of the shoe out of the paths of the wipers in the course of the inward movements of the wipers, the arms being movable to carry the retarder members outwardly over the wipers when they are thus clear of the wipers.

40. In a lasting machine, wipers movable to wipe the margin of an upper inwardly over an insole on a last at the opposite sides of the last, retarder members for pressing the margin of the upper against the wipers to control the upper, said retarder members being movable inwardly over the insole by the wipers, arms controlling said members and mounted for swinging movements widthwise of the shoe about axes extending heightwise of the shoe to carry the members outwardly toward the wipers, other arms mounted similarly to swing widthwise of the shoe for thus operating said first-named arms, and spring means against the resistance of which the first-named arms are movable relatively to said other arms when the retarder members are moved inwardly by the wipers.

41. In a lasting machine, wipers movable to wipe the margin of an upper inwardly over an insole on a last at the opposite sides of the last, retarder members for pressing the margin of the upper against the wipers to control the upper, said retarder members being movable inwardly over the insole by pressure of the wipers thereon, arms controlling said members and mounted for swinging movements widthwise of the shoe about axes extending heightwise of the shoe to carry the members outwardly toward the wipers, other arms mounted similarly to swing widthwise of the shoe for thus operating said first-named arms, the first-named arms being movable relatively to said other arms when the retarder members are moved inwardly by the wipers, and means for moving said members heightwise of the shoe out of the paths of the wipers in the course of the inward movements of the wipers, said first-named arms being movable to carry the retarder members outwardly over the wipers when they are thus clear of the wipers.

42. In a lasting machine, wipers movable to wipe the margin of an upper inwardly over an insole on a last at the opposite sides of the last, retarder members for pressing the margin of the upper against the wipers to control the upper, said retarder members being movable inwardly over the insole by pressure of the wipers thereon, arms controlling said members and mounted for swinging movements widthwise of the shoe about axes extending heightwise of the shoe to carry the members outwardly toward the wipers, other arms mounted similarly to swing widthwise of the shoe for thus operating said first-named arms, devices connecting said other arms to the first-named arms, and means for operating said devices to move the retarder members heightwise of the shoe away from the insole in the course of the inward movements of the wipers.

43. In a lasting machine, wipers movable to wipe the margin of an upper inwardly over an insole on a last at the opposite sides of the last, retarder members for pressing the margin of the upper against the wipers to control the upper, said retarder members being movable inwardly over the insole by pressure of the wipers

thereon, arms controlling said members and mounted for swinging movements widthwise of the shoe about axes extending heightwise of the shoe to carry the members outwardly toward the wipers, other arms mounted similarly to swing widthwise of the shoe for thus operating said first-named arms, devices connecting said other arms to the first-named arms, means for operating said devices to move said retarder members heightwise of the shoe out of the paths of the wipers prior to the completion of the wiping movements of the wipers, and means for operating said other arms to move the retarder members outwardly over the wipers when they are thus clear of the wipers.

44. In a lasting machine, means movable to lay the margin of an upper inwardly over an insole on a last, a retarder member for pressing the margin of the upper against said overlaying means to control the upper, said retarder member being movable inwardly over the insole by pressure of the overlaying means acting thereon through the margin of the upper, and mechanism arranged to be controlled by the inward movement of the overlaying means independently of its pressure on the margin of the upper for moving said retarder member heightwise of the shoe out of the path of the overlaying means.

45. In a lasting machine, means movable to lay the margin of an upper inwardly over an insole on a last, a retarder member for pressing the margin of the upper against said overlaying means to control the upper, said retarder member being movable inwardly over the insole by pressure of the overlaying means acting thereon through the margin of the upper, and a device arranged to be moved heightwise of the shoe by the inward movement of the overlaying means independently of its pressure on the margin of the upper to move said retarder member out of the path of the overlaying means in the course of the inward movement of said means.

46. In a lasting machine, means movable to lay the margin of an upper inwardly over an insole on a last, a retarder member for pressing the margin of the upper against said overlaying means to control the upper, said retarder member being movable inwardly over the insole by pressure of the overlaying means acting thereon through the margin of the upper, a spring against the resistance of which the retarder member is thus movable, and mechanism arranged to be controlled by the inward movement of the overlaying means independently of its pressure on the margin of the upper for moving said retarder member heightwise of the shoe out of the path of the overlaying means, said spring being arranged to move the retarder member in an outward direction over the overlaying means when it is thus withdrawn from said path.

47. In a lasting machine, means movable to lay the margin of an upper inwardly over an insole on a last, a retarder member for pressing the margin of the upper against said overlaying means to control the upper, said retarder member being movable inwardly over the insole by pressure of the overlaying means acting thereon through the margin of the upper, and a device arranged to control said retarder member and relatively to which it is thus inwardly movable, said device being movable heightwise of the shoe by the inward movement of the overlay-

ing means to move said retarder member in a direction away from the insole.

48. In a lasting machine, means movable to lay the margin of an upper inwardly over an insole on a last, a retarder member for pressing the margin of the upper against said overlaying means to control the upper, said retarder member being movable inwardly over the insole by pressure of the overlaying means acting thereon through the margin of the upper, a lever arranged to control said retarder member and relatively to which said member is thus inwardly movable, said lever being supported for swinging movement heightwise of the shoe, and means on said lever arranged to be engaged by said overlaying means in its inward movement to swing the lever and thereby to move said retarder member heightwise of the shoe away from the insole.

49. In a lasting machine, wipers movable to wipe the margin of an upper inwardly over an insole on a last at the opposite sides of the last, wiper carriers movable thus to operate the wipers, retarder members for pressing the margin of the upper against the wipers to control the upper, said retarder members being movable inwardly over the insole by pressure of the wipers thereon, and mechanisms arranged to be controlled by the movements of said wiper carriers for moving said retarder members heightwise of the shoe out of the paths of the wipers in the course of the inward movements of the wipers.

50. In a lasting machine, wipers movable to wipe the margin of an upper inwardly over an insole on a last at the opposite sides of the last, wiper carriers movable thus to operate the wipers, retarder members for pressing the margin of the upper against the wipers to control the upper, said retarder members being movable inwardly over the insole by pressure of the wipers thereon, and devices arranged to control said retarder members and to be moved heightwise of the shoe by action of the wiper carriers thereon to move said members out of the paths of the wipers in predetermined time relation to the movements of the wipers.

51. In a lasting machine, wipers movable to wipe the margin of an upper inwardly over an insole on a last at the opposite sides of the last, wiper carriers movable thus to operate the wipers, retarder members for pressing the margin of the upper against the wipers to control the upper, said retarder members being movable inwardly over the insole by pressure of the wipers thereon, and levers arranged to control said retarder members and mounted for swinging movements heightwise of the shoe, said levers having thereon means arranged to be engaged by said wiper carriers thus to swing the levers and thereby to move the retarder members heightwise of the shoe out of the paths of the wipers.

52. In a lasting machine, wipers movable to wipe the margin of an upper inwardly over an insole on a last at the opposite sides of the last, wiper carriers movable thus to operate the wipers, retarder members for pressing the margin of the upper against the wipers to control the upper, said retarder members being movable inwardly over the insole by pressure of the wipers thereon, and devices arranged to control said retarder members and relatively to which the members are thus inwardly movable, said devices being movable heightwise of the shoe by the inward movements of said wiper carriers to move the retarder members heightwise of the shoe away from the insole.

53. In a lasting machine, wipers movable to wipe the margin of an upper inwardly over an insole on a last at the opposite sides of the last, wiper carriers movable thus to operate the wipers, retarder members for pressing the margin of the upper against the wipers to control the upper, said retarder members being movable inwardly over the insole by the pressure of the wipers thereon, devices arranged to control said retarder members and relatively to which said members are thus inwardly movable, springs against the resistance of which the members are thus movable, and means to cause said wiper carriers in their inward movements to move said devices heightwise of the shoe and thereby to move the retarder members out of the paths of the wipers, said springs being arranged to move said members in outward directions over the wipers when they are thus clear of the wipers.

54. In a lasting machine, wipers movable to wipe the margin of an upper inwardly over an insole on a last at the opposite sides of the last, wiper carriers movable thus to operate the wipers, retarder members for pressing the margin of the upper against the wipers to control the upper, said retarder members being movable inwardly over the insole by pressure of the wipers thereon, arms controlling said members and mounted for swinging movements widthwise of the shoe about axes extending heightwise of the shoe to carry the members outwardly toward the wipers, other arms mounted similarly to swing widthwise of the shoe for thus operating said first-named arms, devices connecting said other arms to the first-named arms, and means to cause said wiper carriers to operate said devices to move the retarder members heightwise of the shoe away from the insole in the course of the inward movements of the wipers.

55. In a lasting machine, wipers movable to wipe the margin of an upper inwardly over an insole on a last at the opposite sides of the last, retarder members for pressing the margin of the upper against the wipers to control the upper, and means for moving said retarder members outwardly toward the side edges of the insole to meet the wipers as the wipers are being moved inwardly, said members being thereafter reversely movable by pressure of the wipers thereon.

56. In a lasting machine, wipers movable to wipe the margin of an upper inwardly over an insole on a last at the opposite sides of the last, retarder members for pressing the margin of the upper against the wipers to control the upper, means for moving said retarder members outwardly toward the side edges of the insole to meet the wipers as the wipers are being moved inwardly, said members being thereafter movable inwardly over the insole by pressure of the wipers thereon, and means for moving said members heightwise of the shoe out of the paths of the wipers in predetermined time relation to the movements of the wipers.

57. In a lasting machine, wipers movable to wipe the margin of an upper inwardly over an insole on a last at the opposite sides of the last, retarder members for pressing the margin of the upper against the wipers to control the upper, arms supporting said retarder members and mounted for swinging movements widthwise of the shoe about axes extending heightwise of the shoe, and means for swinging said arms to carry the retarder members outwardly toward the side edges of the insole to meet the wipers as the wipers are being moved inwardly, said members

and the arms being thereafter reversely movable by pressure of the wipers on the members.

58. In a lasting machine, wipers movable to wipe the margin of an upper inwardly over an insole on a last at the opposite sides of the last, retarder members for pressing the margin of the upper against the wipers to control the upper, means for moving said retarder members outwardly over the insole to meet the wipers as the wipers are being moved inwardly, and means for variably timing the outward movements of said members relatively to the inward movements of the wipers.

59. In a lasting machine, wipers movable to wipe the margin of an upper inwardly over an insole on a last at the opposite sides of the last, wiper carriers movable inwardly thus to operate the wipers, retarder members for pressing the margin of the upper against the wipers to control the upper, and means for moving said retarder members outwardly over the insole toward the wipers in response to the inward movements of said wiper carriers.

60. In a lasting machine, wipers movable to wipe the margin of an upper inwardly over an insole on a last at the opposite sides of the last, wiper carriers movable inwardly thus to operate the wipers, retarder members for pressing the margin of the upper against the wipers to control the upper, and mechanisms arranged to be operated by the inward movements of said wiper carriers to move said retarder members outwardly over the insole to meet the wipers, said mechanisms being adjustable to vary the amount of outward movement thus imparted to the retarder members before they meet the wipers.

61. In a lasting machine, wipers movable to wipe the margin of an upper inwardly over an insole on a last at the opposite sides of the last, wiper carriers movable thus to operate the wipers, retarder members for pressing the margin of the upper against the wipers to control the upper, and means controlled by said wiper carriers for moving said retarder members outwardly over the insole toward the wipers, said members being thereafter movable inwardly over the insole by pressure of the wipers thereon.

62. In a lasting machine, wipers movable to wipe the margin of an upper inwardly over an insole on a last at the opposite sides of the last, wiper carriers movable inwardly thus to operate the wipers, retarder members for pressing the margin of the upper against the wipers to control the upper, arms controlling said retarder members and mounted to swing widthwise of the shoe about axes extending heightwise of the shoe, and means for swinging said arms to move said members outwardly over the insole toward the wipers by the inward movements of said wiper carriers.

63. In a lasting machine, wipers movable to wipe the margin of an upper inwardly over an insole on a last at the opposite sides of the last, wiper carriers movable inwardly thus to operate the wipers, retarder members for pressing the margin of the upper against the wipers to control the upper, and arms controlling said retarder members and mounted to swing widthwise of the shoe about axes extending heightwise of the shoe, said wiper carriers being provided with means arranged to have a cam-like action on said arms to swing the arms outwardly and thus to move said retarder members outwardly over the insole toward the wipers in response to the inward movements of the wiper carriers.

64. In a lasting machine, wipers movable to wipe the margin of an upper inwardly over an insole on a last at the opposite sides of the last, wiper carriers mounted for inward swinging

5 movements toward the shoe about axes extending heightwise of the shoe thus to operate the wipers, retarder members for pressing the margin of the upper against the wipers to control the upper, arms controlling said retarder members and 10 mounted to swing widthwise of the shoe about axes extending heightwise of the shoe, and means for swinging said arms in outward directions to move said retarder members outwardly over the insole toward the wipers by the inward swinging 15 movements of said wiper carriers.

65. In a lasting machine, wipers movable to wipe the margin of an upper inwardly over an insole on a last at the opposite sides of the last, wiper carriers movable inwardly thus to operate

20 the wipers, retarder members for pressing the margin of the upper against the wipers to control the upper, means for moving said retarder members outwardly over the insole toward the wipers by the inward movements of said wiper carriers, and means for variably timing the outward movements of said members relatively to the inward movement of the wiper carriers.

66. In a lasting machine, wipers movable to wipe the margin of an upper inwardly over an

30 insole on a last at the opposite sides of the last, wiper carriers movable inwardly thus to operate the wipers, retarder members for pressing the margin of the upper against the wipers to control the upper, arms controlling said retarder 35 members and mounted to swing in directions widthwise of the shoe about axes extending heightwise of the shoe, plates mounted to swing with said arms, and means on said wiper carriers arranged to have a cam-like action on said plates 40 to swing the arms outwardly and thus to move the retarder members outwardly over the insole toward the wipers by the inward movements of the wiper carriers, said plates being adjustable relatively to the arms to vary the amount of outward movement imparted to the retarder members before they press the upper against the wipers.

67. In a lasting machine, wipers movable to wipe the margin of an upper inwardly over an

50 insole on a last at the opposite sides of the last, wiper carriers movable inwardly thus to operate the wipers, retarder members for pressing the margin of the upper against the wipers to control the upper, means for moving said retarder members outwardly over the insole toward the wipers in response to the inward movements of said wiper carriers, and additional means for thereafter moving said retarder members heightwise of the shoe away from the insole in response to further

60 inward movements of the wiper carriers.

68. In a lasting machine, wipers movable to wipe the margin of an upper inwardly over an insole on a last at the opposite sides of the last, wiper carriers movable inwardly thus to operate

65 the wipers, retarder members for pressing the margin of the upper against the wipers to control the upper, mechanisms arranged to be operated by the inward movements of said wiper carriers to move said retarder members outwardly over the insole toward the wipers, and means arranged to be operated also by the inward movements of the wiper carriers to move said retarder members thereafter heightwise of the shoe out of the paths of the wipers.

70 75 69. In a lasting machine, wipers movable to

wipe the margin of an upper inwardly over an insole on a last at the opposite sides of the last, wiper carriers movable inwardly thus to operate the wipers, retarder members for pressing the margin of the upper against the wipers to control the upper, means for moving said retarder members outwardly over the insole toward the wipers by the inward movements of said wiper carriers,

said members being thereafter movable inwardly over the insole by pressure of the wipers thereon, and means arranged to be operated also by the inward movements of the wiper carriers to move said members heightwise of the shoe out of the paths of the wipers in time relation to the inward movements of the wipers.

BERNHARDT JORGENSEN.

CERTIFICATE OF CORRECTION.

Patent No. 2,346,688.

April 18, 1944.

BERNHARDT JORGENSEN.

It is hereby certified that error appears in the printed specification of the above numbered patent requiring correction as follows: Page 1, second column, line 33, for "ove" read --over--; page 5, second column, line 71, for "the" before "thus" read --are--; page 8, first column, line 19, claim 21, after "engaging" insert --the forepart of--; page 11, first column, line 15, claim 48, for "overlapping" read --overlaying--; page 12, second column, line 27, claim 65, for "movement" read --movements--; and that the said Letters Patent should be read with this correction therein that the same may conform to the record of the case in the Patent Office.

Signed and sealed this 4th day of July, A. D. 1944.

Leslie Frazer

(Seal)

Acting Commissioner of Patents.
